Picture of body brush in article entitled, How to Dry Brush Your Skin (and Why You Should!) [on-line]. Published on the Internet Mar. 10, 2015; retrieved from the Internet on May 28, 2017. URL: <<https://beautyeditor.ca/2015/03/10/how-to-dry-brush-your-body>>. (7 pages) (Year: 2017).*

Primary Examiner — Karen E Eldridge Powers(74) Attorney, Agent, or Firm — Banner & Witcoff, Ltd.(57) CLAIM

The ornamental design for a body brush, as shown and described.

DESCRIPTION

FIG. 1 is a front, top perspective view of a body brush showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken line showing of the various unshaded elements of the body brush represents unclaimed subject matter and forms no part of the claimed design.

1 Claim, 7 Drawing Sheets(56)
